UNITED STATES PATENT OFFICE.

LEWIS R. HEIM, OF DANBURY, CONNECTICUT, ASSIGNOR, BY MESNE ASSIGNMENTS, TO CINCINNATI GRINDERS INCORPORATED, OF CINCINNATI, OHIO, A CORPORATION OF OHIO.

GRINDING APPARATUS.

Application filed February 8, 1921. Serial No. 443,390.

This invention relates to grinding apparatus and more particularly to grinding apparatus adapted to grind the surfaces of cylindrical articles. One of the objects of the 5 invention is to provide practical apparatus of the above nature capable of a broad field of efficient use. Another object is to provide grinding apparatus of compact and simple construction and efficient and accurate 10 action. Another object is to provide a simple and effective attachment formed for ready connection with and removal from a grinding machine and adapted substantially to broaden the field of use of such machine. Other objects will be in part obvious and in part pointed out hereinafter.

The invention accordingly consists in the features of construction, combinations of elements and arrangement of parts which 20 will be exemplified in the structure herein-after described and the scope of the application of which will be indicated in the following claims.

In the accompanying drawings in which 25 is shown one of various possible embodiments of this invention,

Figure 1 is a plan of the same;

Figure 2 is a sectional elevation taken along the line 2—2 of Figure 1;

Figure 3 is a sectional elevation taken along the line 3—3 of Figure 1;

Figure 4 is a sectional view on an enlarged scale of parts appearing in Figure 3; and

Figure 5 is a sectional elevation taken 35 along the line 5—5 of Figure 4.

Figure 6 is a perspective view on a small scale of the work carrier.

Similar reference characters refer to similar parts throughout the several views of 40 the drawings.

Referring now to Figure 2 of the drawings, there is indicated a supporting frame or stand 10 of any suitable construction provided with a bed 11 having ways 12 extending longitudinally thereof, that is in a right-and-left direction with respect to Figure 2. On these ways is mounted a lower carriage 13 capable of movement by any suitable means along the ways 12 as is common in the construction of ordinary external grinders.

Upon the lower carriage 13 which is

shown in plan in Figure 1 of the drawings, is mounted a head stock 14 driven as by the pulley 15 with belt 16 and provided 55 with a suitable face plate 17.

The upper surface of this carriage is provided with ways indicated at 18 on Figure 3 of the drawings, and slidably mounted on these ways is a tail stock 19 provided with 60 the ordinary means for adjusting it longitudinally of the machine and clamping it in adjusted position.

Mounted on a rearward extension 20 of the frame of the machine as shown in Figure 3 of the drawings is a carriage or slideable support 20^a supported on ways 21 on which it may travel in a direction toward and away from the bed 13 and with respect to which it may be locked in position as by 70 means of the bolt 22. This carriage is provided with a pair of heavy bearings 23 for a shaft 24 driven by the pulley 25 and belt 26 which is protected by a hood or housing 27. Shaft 24 carries a grinding wheel 28 75 which is driven at high speed preferably in the direction indicated by the arrows in Figure 1 of the drawings. By suitable adjustment of the carriage 20 this grinding wheel may be moved to bring its operative surface 80 at any desired distance from the axis of the head stock and tail stock hereinbefore described. This adjustment furthermore not only provides for altering the point action of the surface of the grinding wheel but 85 compensating for any wear on the latter part.

It will thus be seen that if work be mounted upon the centers of the head stock and tail stock hereinbefore described and rotated 90 by a suitable dog, its surface may be ground by bringing forward the rapidly rotating grinding wheel to the desired point and moving the bed or carriage 13 back and forth in a direction lengthwise of the machine. It may also be noted at this point that this lower carriage or bed 13 comprises upper and lower members 13^a and 13^b respectively, which although generally moving as a unit are nevertheless relatively movable 95 about a vertical axis on the curved ways or guides 29 and 30. This provision is made to permit the upper portion 13^a of the carriage to be swung slightly into an oblique

relation with the length of the lower portion 13^b and clamped in such position. With this adjustment the axis of the parts mounted on the centers of the head stock and tail stock will be correspondingly inclined with respect to the axis of the shaft 24, and upon a longitudinal movement of the carriage 13 with respect to the grinding wheel, a surface of tapering form will be ground. Obviously this angular adjustment may be employed to correct any deviation from parallelism of the above axes when it is desired to grind a truly cylindrical surface.

Mounted upon the ways 18 as shown in Figures 3 and 4 of the drawings, is a device or attachment in which certain of the more important features of this invention reside. This device comprises a recess or support 31 clamped on the bed in any desired manner, as by means of the cap screw 31^a, and provided at its forward end, that is toward the front of the machine, with a sleeve or bearing 32. Rotatably mounted in this bearing is a shaft 33 threaded as at 34 and provided with a hand wheel 35 and collar 36 respectively adapted to turn the shaft and prevent its movement in the bearing 32. This shaft 33 is threaded into a slide or carriage 37 which travels on ways 38 formed on the support 31. As the hand wheel 35 is turned, the slide 37 is accordingly moved transversely of the machine, that is, toward or away from the axis of the centers of the head and tail stocks. The slide 37 is yieldingly held in adjusted position by means of a spring 39 interposed between the head of a screw 40 and a cross-piece 41 which bears against the sides of a slot 42 in the support 31, through which slot the screw passes.

There is thus exerted a yielding frictional pressure tending to clamp the slide 37 to the support 31 and yet permitting manual adjustment of the latter.

Formed on the slide 37 is an abutment or flange 43 provided with a recess 44 in which there is held by the screw 45 a flat plate 46. Also mounted on the abutment 43 as by means of the bolt 47 is a plate 48 parallel to the plate 46. Clamped between these plates is a support or carrier for rolls 49 having at its upper edge an inserted wear piece of hard steel 50. This carrier 49 as shown in Figure 6 of the drawings, has preferably substantially parallel sides or faces and may be positioned or clamped between the plates 46 and 48 (see Fig. 5) so that its upper surface is downwardly inclined to any desired degree in a direction toward the head stock of the machine, the slots 51 through which the bolts 47 loosely pass permitting adjustment of such inclination as well as adjustment of the carrier 49 vertically with respect to the grinding wheel.

Between the plates or flanges 46 and 48 there is thus provided a supporting surface

along which cylindrical objects may be fed and this trough may be in effect raised or lowered with respect to the horizontal plane of the axis of the grinding wheel as hereinabove described and its inclination with the horizontal adjusted at will for a purpose hereinafter described. Also by the substitution of carriers 49 of different thicknesses, rolls or other cylindrical objects of different diameters may be accommodated.

Leading to a point between the plates 48 and 46 is a feed trough 52 supported as by the bent rod 53 which is removably mounted in any suitable manner on the machine.

For use in conjunction with the device above described, there is mounted on the centers of the head and tail stock and driven by a suitable dog, an arbor or mandrel 54 having fixed thereon a wheel 55 which may preferably be an emery wheel or the like. This latter wheel is rotated as indicated by the arrow in Figure 1 of the drawings, in what is termed the opposite direction with respect to the direction of rotation of the grinding wheel. In other words, the operative surfaces of these two wheels co-acting with opposite sides of articles supported on the carrier 49 as hereinabove described, travel in opposite directions; that is, the grinding wheel surface will move downwardly toward the carrier whereas the opposing surface of the wheel 55 will move upwardly or away from the carrier.

Considering now the action of this apparatus, it may first be noted that it may be employed as hereinbefore described to grind cylindrical or tapering surfaces of articles mounted directly on the centers of the head and tail stocks in place of the arbor 54. When this is done, the fixture or attachment 31 is removed and the grinding wheel moved forwardly to co-act with the surface of the article thus mounted. Suitable angular adjustment having been made between the upper and lower portions of the carriage 13 the latter is moved back and forth longitudinally of the machine and a cylindrical or tapering surface is ground. When however it is desired to grind a large number of articles such as the rolls 56, the fixture 31 and trough 62 are mounted in position and the arbor 54 with its wheel 55 mounted upon the centers. The various parts are thereupon adjusted to fit the diameter of rolls which it is desired to grind and support them in a position between the opposed surfaces of the wheels 28 and 55 contacting therewith on the opposite sides. The wheel 28 is thereupon driven at a high rate of speed and the wheel 55 driven at a relatively very low rate of speed. Rollers are then fed continuously to the trough 52 and slide by gravity into the grip of these opposed wheels. The grinding wheel 28 simply grinds at a high rate of speed all sur-

faces brought into contact therewith, but due to such high speed exerts comparatively little frictional effect on the roll. The wheel 55 however, although turning much 5 more slowly than the wheel 28, continually tends to lift the surface of the roller which it contacts, thus causing it to rotate in the direction indicated by the arrow in Figure 2 of the drawings, and due to the small diameter of the roll, this rotation is substantially rapid. Furthermore the roll having an inclined relation with respect to the axis of the wheel 55 as shown in the drawings, the latter wheel tends to feed the roller longitudinally of the machine in a direction toward the left, having reference to Figure 2 of the drawings. Also, the rate of feed may be varied by adjusting the inclination of the carrier with the horizontal, whereby the 10 relative inclination of the path of travel of the rolls with respect to the path of the surface of the regulating wheel 55 may be adjusted at will as hereinbefore described. Thus as each successive roll is brought with 15 in the grip of the wheels, it is rapidly rotated and accurately ground and automatically passes out between the left-hand pair of plates 46 and 48 from which it is carried away by any suitable trough, diagrammatically indicated at 57. This operation may 20 be carried on at a high rate of speed and it is to be understood that rolls or other cylindrical devices of various lengths and diameters may not only be rapidly but accurately ground. Furthermore, as hereinbefore noted, the machine is readily adaptable 25 to grinding larger parts more slowly or in tapering form by the mounting of such parts directly on the centers in place of the 30 arbor 54.

It will thus be seen that there is provided apparatus in which the several objects of this invention are achieved.

As various possible embodiments might 45 be made of the above invention and as various changes might be made in the embodiment above set forth, it is to be understood that all matter herein set forth or shown in the accompanying drawings is to be interpreted as illustrative and not in a limiting 50 sense.

I claim:

1. In apparatus of the general nature of that herein described, in combination, a 55 grinding wheel adapted to be rotated at a relatively high speed, means for rotatably supporting and driving said grinding wheel, means adapted normally to detachably support a cylindrical work piece for rotation 60 about a predetermined axis and to rotate said work piece relatively slowly while said grinding wheel performs a grinding operation thereon, a regulating wheel detachably supported in said work supporting and rotating means and rotated by the latter rela-

tively slowly and in a direction to present an operative surface adjacent that of the grinding wheel traveling in a direction opposite from the direction of travel of the operative surface of said grinding wheel, thereby to 70 form with said grinding wheel a grinding throat for receiving work of round section, and means for supporting work of round section in the grinding throat formed by and between said adjacent oppositely-moving 75 surfaces of said two wheels, whereby said regulating wheel controls the rotation of said work of round section in said grinding throat while the grinding wheel performs a grinding operation thereon. 80

2. In apparatus of the general nature of that herein described, in combination, a grinding wheel, a regulating wheel, said wheels being adapted to present adjacent operative surfaces traveling in opposite directions, a carrier extending between said wheels for supporting round bodies in operative relation to the operative surfaces of said wheels, means for adjusting said carrier toward or away from the operative surface 90 of one of said wheels, and continuously acting means for yieldingly holding said carrier in adjusted position. 95

3. In apparatus of the general nature of that herein described, in combination, a 100 grinding wheel, a regulating wheel, said wheels being adapted to present adjacent operative surfaces traveling in opposite directions, a carrier for supporting round bodies between the operative surfaces of said 105 wheels, a carriage for mounting said carrier between said wheels and adapted to be adjusted toward or away from the operative surface of one of said wheels, and continuously acting means for frictionally holding 110 said carriage in adjusted position. 115

4. In apparatus of the general nature of that herein described, in combination, a 120 grinding wheel, a regulating wheel, said wheels being adapted to present adjacent operative surfaces traveling in opposite directions, a carriage mounted substantially between said wheels and adapted to be adjusted toward or away from the operative surface of one of said wheels, continuously acting 125 means for yieldingly holding said carriage in adjusted position, a carrier for supporting round bodies between the operative surfaces of said wheels mounted upon said carriage, and means for adjusting the relative inclination between said carrier and the path of the operative surface of said regulating wheel. 130

5. In apparatus of the general nature of that herein described, the combination, with an external grinder comprising a supporting frame, a grinding wheel rotatably mounted at the rear of said frame, and centers adapted normally to rotatably support work in operative relation to said grinding wheel, of means attachable to said frame and pro-

- viding a carrier for supporting round bodies in operative relation to said grinding wheel and having means operable from a portion of said frame remote from said grinding 5 wheel for adjusting said carrier in a direction transverse to the axis of said round bodies, and a regulating wheel adapted to be rotatably supported on said centers for rotating said round bodies on said carrier.
10. 6. In apparatus of the general nature of that herein described, in combination, a grinding wheel adapted to be rotated at a relatively high speed, means for rotatably supporting and driving said grinding wheel, 15 means adapted normally to detachably support a cylindrical work piece for rotation about a predetermined axis and to rotate said work piece relatively slowly while said grinding wheel performs a grinding operation thereon, a regulating wheel detachably supported in said work supporting and rotating means and rotated by the latter relatively slowly and in a direction to present an operative surface adjacent that of the grinding 20 wheel traveling in a direction opposite from the direction of travel of the operative surface of said grinding wheel, thereby to form with said grinding wheel a grinding throat for receiving work of round section, a 25 carrier extending between said wheels for supporting work of round section in operative relation to the grinding throat formed by and between the oppositely-moving operative surfaces of said two wheels, whereby 30 said regulating wheel rotates the work in said grinding throat while the grinding wheel performs a grinding operation thereon, and the path of travel of the work axially along said work carrier being inclined with 35 respect to the path of travel of the operative surface of said regulating wheel, whereby the latter acts to feed the work along said grinding throat and past said grinding wheel.
7. In apparatus of the general nature of 40 that herein described, in combination, a main frame, a grinding wheel, means for driving said grinding wheel at relatively high speed, a head stock and a tail stock mounted on said frame and providing a 45 live center and a dead center adapted normally to detachably support a round work piece and to rotate the latter relatively slowly about a predetermined axis, thereby to permit a grinding operation to be performed thereon by said grinding wheel, a 50 regulating wheel detachably supported by said centers and driven from said head stock relatively slowly and in a direction so that the adjacent operative surfaces of said two 55 wheels move in opposite directions and form a grinding throat for receiving work of round section, the driving connection between said regulating wheel and said live center being detachable and including a dog, 60 and a carrier extending between said wheels 65 for supporting work of round section in operative relation thereto, whereby said regulating wheel controls the rotation of said work while the grinding wheel performs a grinding operation thereon, and means for adjusting said regulating wheel in a direction lengthwise of said carrier to bring its operative surface in juxtaposition to the operative surface of said grinding 70 75 80 85 90 95 100 105 110 115 120 125 130
- for supporting work of round section in operative relation thereto, whereby said regulating wheel controls the rotation of the work in said grinding throat while the grinding wheel performs a grinding operation thereon.
8. In apparatus of the general nature of that herein described, in combination, a carrier for supporting round bodies, a grinding wheel rotatably mounted in operative relation to said carrier and on one side thereof for grinding said bodies, a regulating abrasive wheel rotatably mounted on the other side of said carrier for rotating said round bodies during the operation thereon by said grinding wheel, said wheels being adapted to present operative surfaces traveling in opposite directions, and means for adjusting said regulating wheel in a direction lengthwise of said cylindrical body relative to the operative surface of said grinding wheel.
9. In apparatus of the general nature of that herein described, in combination, a carrier for supporting work of round section, a grinding wheel rotatably mounted in operative relation to said carrier and on one side thereof for grinding said work, a peripheral regulating abrasive wheel rotatably mounted on the other side of said carrier for rotating said work of round section during the operation thereon by said grinding wheel, said wheels being adapted to present operative surfaces traveling in opposite directions, means for adjusting said regulating wheel in an axial direction relative to the operative surface of said grinding wheel, and means for adjusting the operative surface of said grinding wheel toward or away from the operative surface of said regulating wheel.
10. In apparatus of the general nature of that herein described, in combination, a main frame, a grinding wheel, means for driving said grinding wheel at relatively high speed, means on said frame adapted normally to detachably support a round work piece and to rotate the latter relatively slowly about a predetermined axis while the grinding wheel performs a grinding operation thereon, a regulating wheel detachably supported by said last-mentioned means and rotated relatively slowly thereby and in a direction such that the adjacent operative surfaces of said two wheels travel in opposite directions, a carrier extending between said wheels for supporting work of round section in operative relation thereto, whereby said regulating wheel controls the rotation of said work while the grinding wheel performs a grinding operation thereon, and means for adjusting said regulating wheel in a direction lengthwise of said carrier to bring its operative surface in juxtaposition to the operative surface of said grinding

wheel and to cause said two wheels to form a grinding throat for receiving work of round section.

11. In apparatus of the general nature of that herein described, the combination with an external grinder comprising a supporting frame, a peripheral grinding wheel rotatably mounted at the rear of said frame, and centering and driving means adapted 10 normally to detachably support and rotate relatively slowly a cylindrical work piece for grinding operation thereon by said grinding wheel, of means attachable to said frame and providing a carrier for supporting round bodies adjacent to the peripheral operative surface of said grinding wheel, and a regulating abrasive wheel adapted to be rotatably and detachably supported on said centering and driving means and in 20 juxtaposition to said grinding wheel and adapted to be driven by said centering and driving means at a relatively slow speed and in a direction so that the adjacent operative surfaces of said two wheels travel in opposite directions, whereby said regulating wheel rotates said round bodies in said grinding throat while the grinding wheel performs a grinding operation thereon.

12. In apparatus of the general nature of that herein described, the combination with an external grinder comprising a supporting frame, a peripheral grinding wheel rotatably mounted at the rear of said frame, and a head stock and a tail stock each providing 30 a supporting center for normally detachably supporting and rotating a round work piece relatively slowly and about a predetermined axis for action thereon by the peripheral operative surface of said grinding wheel, of means adapted to be secured to said frame and providing a carrier for rotatably supporting round bodies adjacent to said grinding wheel, and a regulating wheel adapted to be mounted on and driven at a relatively 40 low speed from said centers on said head stock and tail stock and having its operative face juxtaposed to that of the grinding wheel, thereby to form a grinding throat for said bodies on said carrier, said regulating 50 wheel being driven in a direction so that the adjacent operative surfaces of said two wheels move in opposite directions and acting to control the rotation of the body in said grinding throat.

13. In apparatus of the general nature of that herein described, the combination with an external grinder comprising a supporting frame, a peripheral grinding wheel rotatably mounted at the rear of said frame, and 60 a head stock adapted normally to have detachably connected thereto and to rotate relatively slowly a round work piece in operative relation to said grinding wheel and while the latter performs grinding upon the 70 work piece, of a carrier adapted to support

work of round section adjacent to the peripheral operative surface of said grinding wheel and detachably mounted upon the frame, and a regulating wheel detachably mounted in connection with said head stock in juxtaposition to said grinding wheel to form a grinding throat with said grinding wheel for receiving therein work of round section on said carrier, and driven from said head stock at a relatively low speed and in a direction to present an operative surface traveling opposite from the direction of travel of the operative surface of said grinding wheel, whereby said regulating wheel controls the rotation of said work in said grinding throat 80 during grinding action thereon by said grinding wheel.

14. In apparatus of the general nature of that herein described, the combination with an external grinder comprising a supporting frame, a peripheral grinding wheel rotatably mounted at the rear of said frame, and a head stock and a tail stock, said head stock being adapted normally to have detachably connected thereto and to rotate relatively 90 slowly a round work piece and said tail stock being provided with a supporting center for said round work piece, whereby the latter is rotated relatively slowly about a predetermined axis during grinding action thereon by said grinding wheel, of means adapted to be secured to said frame and providing a carrier for rotatably supporting cylindrical bodies adjacent to the peripheral operative surface of said grinding wheel, a regulating wheel detachably mounted in connection with said head stock in juxtaposition to said grinding wheel to form therewith a grinding throat for receiving said bodies on said carrier and driven relatively slowly from 95 said head stock and in part supported upon said tail stock center, thereby to control the rotation of said cylindrical bodies in said grinding throat and during operation thereon by said grinding wheel.

15. In apparatus of the general nature of that herein described, in combination, a main support adapted to be detachably secured to the ways of a machine, a carriage mounted on said support, means for adjustably moving said carriage on said support and in a direction transverse to the direction of said ways, a work carrier extending in the general direction of said ways for supporting round objects, and means for mounting said carrier on said carriage adapted to permit vertical adjustment thereof with respect to said ways.

16. In apparatus of the general nature of that herein described, in combination, a main support adapted to be detachably secured to the ways of a machine, a carriage mounted on said support, means for adjustably moving said carriage on said support and in a direction transverse to the direction of 125

said ways, a work carrier extending in the general direction of said ways for supporting round objects, and means for mounting said carrier on said carriage adapted to permit adjustment of the inclination of said carrier with the horizontal.

17. In apparatus of the general nature of that herein described, in combination, a main support adapted to be detachably secured to the ways of a machine, a carriage mounted on said support, means for adjustably moving said carriage on said support and in a direction transverse to the direction of said ways, a work carrier extending in the general direction of said ways for supporting round objects, and adjustable means for mounting work carriers of different widths on said carriage.

18. In apparatus of the general nature of that herein described, in combination, a main frame provided with ways extending longitudinally thereof, a tail stock and a driving head stock provided with centers mounted on said ways, an auxiliary frame provided with ways extending transversely of said first-mentioned ways, a grinding wheel rotatably mounted on said transverse ways and adjustable thereon toward or away from said first-mentioned ways, a regulating wheel detachably mounted in operative relation to said grinding wheel on said centers and adapted to be driven from said head stock, said wheels being adapted to present operative surfaces traveling in opposite directions, and a work carrier extending between the operative surfaces of said wheels and detachably mounted on said longitudinally extending ways.

19. In apparatus of the general nature of that herein described, in combination, a main frame provided with ways extending longitudinally thereof, a tail stock and a driving head stock provided with centers mounted on said ways, an auxiliary frame provided with ways extending transversely of said first-mentioned ways, a grinding wheel rotatably mounted on said transverse ways and adjustable thereon toward or away from said first-mentioned ways, said centers being adapted normally to rotatably support cylindrical work to be positively rotated from said head stock and to be operated upon by said grinding wheel, a carrier for supporting round work not adapted to be mounted on said centers of said head and tail stocks and for carrying said work in operative relation to said grinding wheel, means for

mounting said carrier on said frame in operative relation to said grinding wheel, and a regulating wheel adapted to be mounted on said centers and driven from said head stock to rotate said round work on said carrier, said wheels being adapted to present operative surfaces traveling in opposite directions.

20. In apparatus of the general nature of that herein described, in combination, a main frame provided with ways extending longitudinally thereof, a tail stock and a driving head stock provided with centers mounted on said ways, an auxiliary frame provided with ways extending transversely of said first-mentioned ways, a grinding wheel rotatably mounted on said transverse ways and adjustable thereon toward or away from said first-mentioned ways, a regulating wheel mounted in operative relation to said grinding wheel on said centers and adapted to be driven from said head stock, said wheels being adapted to present operative surfaces traveling in opposite directions, a work carrier extending between the operative surfaces of said wheels and adjustable toward or away from one of said wheels, and means for detachably securing said adjustable work carrier to said frame.

21. In apparatus of the general nature of that herein described, in combination, a main frame provided with ways extending longitudinally thereof, a tail stock and a driving head stock provided with centers mounted on said ways, an auxiliary frame provided with ways extending transversely of said first-mentioned ways, a grinding wheel rotatably mounted on said transverse ways and adjustable thereon toward or away from said first-mentioned ways, a regulating wheel detachably mounted in operative relation to said grinding wheel on said centers and adapted to be driven from said head stock, said wheels being adapted to present operative surfaces traveling in opposite directions, a support detachably secured to said longitudinal ways, a carriage extending substantially between said two wheels mounted on said support and movable thereon toward or away from one of said wheels, and a work carrier mounted on said carriage for supporting work of round section in operative relation to said wheels.

In testimony whereof, I have signed my name to this specification this twenty-fourth day of January, 1921.

LEWIS R. HEIM.
